UNITED STATES PATENT OFFICE.

WILLIAM JAMES, OF BROOKLYN, ASSIGNOR TO THE NATIAN MANUFACTURING COMPANY, OF NEW YORK, N. Y.

LUBRICATOR.

SPECIFICATION forming part of Letters Patent No. 442,321, dated December 9, 1890.

Application filed May 21, 1890. Serial No. 352,621. (No model.)

To all whom it may concern:

Be it known that I, WILLIAM JAMES, of the city of Brooklyn, Kings county, State of New York, have invented certain new and useful 5 Improvements in Lubricators, of which the following is a specification.

This invention relates to certain new and useful improvements in sight-feed lubricators. It refers more particularly to what are 10 termed "single-connected" lubricators, in which the admission of steam into the condensing-chamber of the lubricator and the delivery of the oil to the parts to be lubricated are effected by one duct or channel.

15 The object of my invention is to increase the efficiency of such single-connected lubricators by simplifying their construction and manufacture.

The improvements will be more fully understood by reference to the accompanying drawings, in which—

Figure 1 is a longitudinal vertical section on line 1 1 of Fig. 3. Fig. 2 is a longitudinal vertical section on line 2 2 of Fig. 3. Fig. 3 is 25 a horizontal cross-section on line 3 3 of Fig. 2, omitting brackets and connections.

A is the body of the lubricator, containing the oil, and is provided with a filler B, which when removed discloses an opening in the 30 body through which the reservoir is filled with oil.

C is an externally-threaded shank cast in one with the main body of the lubricator. By means of this neck the lubricator is connected 35 to the main steam-pipe, steam-chest, or cylinder of a steam-engine in the ordinary well-known manner, a valve being interposed between the neck C and the steam pipe, chest, or cylinder for the purpose of controlling the 40 admission of the steam to the lubricator.

D is the condensing-chamber, screwed to the top of the lubricator-body. Steam is conveyed into the condenser D from neck C by means of the pipe E, which is screwed into the 45 condenser in such a way that an air-chamber is formed in the condenser above the horizontal branch of pipe E. The horizontal branch of pipe E is closed at the end, and a series of holes is provided, forming a spray and deflecting the steam toward the inner wall of

the condenser in a fine film, thereby effecting a thorough and rapid condensation.

F is a pipe conveying the condensed water from the condenser to near the bottom of chamber A, the admission of the water into 55 the cup being controlled by valve G.

H is the waste-valve to drain the cup of its contents when required.

I is the oil-pipe conveying the oil from the oil-chamber through nipple K, water-filled 60 glass L, and channels M and M' into neck C.

In single-connected lubricators as heretofore constructed the pipe conveying the steam to the condenser generally has been located inside of the chamber, or, if located outside 65 of the condenser, has been connected with it at its top. In the first case the lubricator, as a rule, becomes too hot, whereby the formation of a steady continuous feed is prevented, while in the second case, when the 70 lubricator has been left standing under steam over night, for instance, the condenser filled up to the very top and caused what is termed in the art "plugging," preventing the necessary circulation for the proper operation of 75 the lubricator. By connecting the pipe E at the side of the condenser more or less air will accumulate above the tube, preventing the filling up of the condenser and effecting a drainage of the surplus condensation under 80 more or less pressure proportionate to the quantity of the accumulated air.

The operation of the improved lubricator is as follows: Steam being admitted into condenser D and condensing there, the resulting 85 water of condensation passes down the pipe F into the reservoir A, the admission of the water being controlled by valve G. The water thus admitted into the reservoir A will displace the oil, which will float on the water and 90 enter the tube I. Upon opening the regulating-valve N the oil will pass in drops through nipple K, glass L, and channels M and M' into the duct C, and thence to the parts to be lubricated.

I am aware that a double-connected lubricator has been proposed into which the pipe leading the steam to the condenser entered the latter at its side, and I am also aware that a lubricator has been constructed provided 95 100

with a top and bottom pipe both entering the condenser, the top of the bottom pipe being closed and provided with side holes for the purpose of deflecting and spraying the steam. 5 I do not therefore intend to claim these features, broadly; but I believe myself to be the first who has embodied these valuable features in the most effective and simple manner in a single-connected lubricator.

10 What I claim, therefore, as new, and desire to secure by Letters Patent, is—

In a single-connected lubricator, the combination of the following elements: the single duct or channel C for the admission of steam 15 and the delivery of oil, the outside pipe E,

entering the condenser at its side and leaving an air-space above the point of entrance, the branch of the pipe which enters the condenser being closed and provided with a series of holes, condenser D, reservoir A, water-pipe 20 F, valve G, waste-valve H, regulating-valve N, nipple K, glass L, and ducts M and M', all arranged as and for the purpose specified.

In testimony whereof I have hereunto set my hand this 19th day of May, 1890.

WILLIAM JAMES.
